Primary Examiner — Ian Simmons*Assistant Examiner* — Shannon Morgan(74) *Attorney, Agent, or Firm* — Lucas & Mercanti, LLP(57) **CLAIM**

The ornamental design for a hoop carousel, as shown and described.

DESCRIPTION

FIG. 1 is a front, right perspective view of a hoop carousel showing my new design;

FIG. 2 is a front elevational view, the rear elevational view being an identical mirror image thereof;

FIG. 3 is a left side elevational view, the right side elevational view being an identical mirror image thereof;

FIG. 4 is a top plan view thereof; and,

FIG. 5 is a bottom plan view thereof.

The broken lines in FIGS. 1–5 of the hoop carousel are for the purpose of illustrating environment, and form no part of the claimed design.
